UNITED STATES PATENT OFFICE.

CLARENCE WILBUR TABER, OF CHICAGO, ILLINOIS.

DESIGN FOR A FRATERNAL EMBLEM.

No. 39,987.

Specification for Design.

Patented May 18, 1909.

Application filed February 10, 1909. Serial No. 477,260. Term of patent 14 years.

To all whom it may concern:

Be it known that I, CLARENCE WILBUR TABER, a citizen of the United States, and resident of Chicago, in the county of Cook and State of Illinois, have invented a new, original, and ornamental Design for a Fraternal Emblem, of which the following is a full, clear, and exact specification, reference being had to the accompanying sheet of drawings, forming part thereof.

The figure in the drawings is a plan view of the fraternal emblem showing my new design.

I claim:

The ornamental design for a fraternal emblem, as shown.

CLARENCE WILBUR TABER.
